UNITED STATES PATENT OFFICE.

IRA G. NICKS, OF DENVER, COLORADO, ASSIGNOR TO THE JOY TOY MANUFACTURING COMPANY, OF DENVER, COLORADO, A CORPORATION OF COLORADO.

TOY VEHICLE.

Application filed November 14, 1925. Serial No. 69,015.

This invention relates to improvements in toy vehicles of the foot propelled type.

It is the object of this invention to produce a vehicle that shall have the general appearance of an aeroplane and be so constructed that it can be readily propelled and steered by the child operator.

My invention has for its further object the improvement of the construction of the propelling and steering apparatus and the manner of mounting the body and of securing the seat thereto.

The above and other objects that will become apparent as the description proceeds are attained by means of a construction and arrangement of parts that will now be described in detail, reference for this purpose being had to the accompanying drawings in which the preferred embodiment of the invention has been illustrated and in which:

Fig. 1 shows a top plan view of the improved toy;

Fig. 2 is a side elevation of the invention, parts being broken away to better disclose the construction;

Fig. 3 is a section taken on line 3—3, Fig. 2 and shows a detail of the bearings in which the crank shaft is journalled;

Fig. 4 is a transverse section taken on line 4—4, Fig. 2;

Fig. 5 is a section taken on line 5—5, Fig. 4;

Fig. 6 is a section taken on line 6—6, Fig. 2;

Fig. 7 is a section taken on line 7—7, Fig. 4 and shows a top plan view of the steering mechanism;

Fig. 8 is a section taken on line 8—8, Fig. 4 and shows a detail of construction, and

Fig. 9 is a section taken on line 9—9, Fig. 7.

The body is built about a framework comprising two members 1 and 2 of wood, as shown, or of metal. These members are curved so as to conform to the outline shown in Fig. 1. To these side members the sheet metal member 3, forming the body, is secured by means of nails or screws 4. Secured to the underside of members 1 and 2 near the front ends thereof by means of bolts 5 are springs 6 to the front ends of which the channel 7 is secured by means of bolts or rivets 8. Mounted for rotation about the pivots 9, which are located near the ends of the bar 7, are forks 10 to the lower ends of

which the front wheels 11 are pivoted. Secured to the transverse member of each fork 10 is an arm 12, one end 13 of which is bent upwardly so as to hold the arm from rotating about the pivot 9. A connecting bar 14 joins the free ends of the arms 12 for the purpose of producing simultaneous equiangular rotation of the steering wheels about pivots 9. A steering post 15 projects through a hole in the channel and has its upper end 16 extending through a hole in the top of the body member (Fig. 5). The parts 15 and 16 are connected by means of a T 17 to which the steering lever 18 is fastened. For the purpose of holding the steering post 15 from sliding downwardly, I employ a washer 19 and pin 20 arranged as shown in Fig. 9. The lower end of the steering post is flattened in the manner indicated by numeral 21 in Fig. 9 and this flattened end is pivoted to the bars 14 and 22. By moving the lever 18 to one side or the other, the front wheels may be rotated about the pivots 9 and the direction of the vehicle thereby controlled. The rear end of the vehicle is supported on a single wheel 23 nonrotatably secured to a crank shaft having two opposed cranks 24 and 25. The ends of the crank shaft which have been designated by numerals 26 and 27 are journalled in a bearing formed in one end of L 28 (Fig. 3). The other ends of these L's are threaded into flange couplings 29 that are secured to the underside of the frame members 1 and 2. A rod 30 extends transversely of the body member at a point near the front end but to the rear of the channel 7. Pivotally mounted on the rod 30 are two U-shaped pedal members 31, a ferrule 32 spaces the adjacent vertical arms of these members in the manner shown in Fig. 4. Connecting rods 33 have their front ends pivoted at 34 to the inside vertical members of the pedals 31 and are connected at their rear ends to the cranks 24 and 25. By oscillating the pedals 31 the drive wheel can be rotated in either direction whereby the vehicle can be made to move in either direction. A seat 35 is supported on the raised rear ends of the cantilever springs 36 whose front ends are bolted to the upper sides of the side members 1 and 2 in the manner shown in Fig. 2. Secured to the rear end of the body are two tail fins 361 and 37, the former of which lies in a horizontal plane and the latter in a vertical plane. Fin 37 has a slot 38 extending rear-

wardly and fin 361 a corresponding slot 39 extending forwardly; these slots receive the respective unslotted portion of the other fin. The front end of the body has a strip 40 that 5 represents the outer surface of a radiator shell and the front surface is provided with an expanded metal member 41 that resembles a radiator core. A propeller 42 is pivotally mounted at 43. Transverse wings 44, 45 and 10 46 are secured to the body of the machine and gives it the appearance of a biplane. The wing 44 is spaced from the top of the body by means of a block 47 and the ends of wings 45 and 46 are secured to longitudinal 15 cleats 48 that are secured to the body 3 by means of bolts 49. Vertical braces 50 extend between the upper wing 44 and the lower wings 45 and 46 and diagonal braces 51 extend from the upper wing to the body 3, 20 thereby producing a rigid structure.

By making the rear wheel 23 the drive wheel, greater speed may be obtained as this wheel may be made as large as desired, whereas, the front wheels must be limited in 25 size if a pleasing appearance is to be obtained. I am aware that attempts have been made to employ the front wheels for driving and the rear wheel for steering, but this is not satisfactory because the front wheels must 30 be made small, which limits the speed and a machine steered by the rear wheel has the peculiarity of swinging the rear end from side to side in a very unpleasant manner.

Having now described the invention, what 35 is claimed as new is:

1. A toy vehicle comprising, in combination, a base frame embodying a pair of side members converging towards the rear, a sheet metal shell secured to said side members so as to form a body resembling an 40 aeroplane body, a pair of cantilever springs secured at their rear ends to the underside of said side members, a transverse bar secured to the front ends of said springs, U-shaped forks pivotally attached to the ends 45 of said bar, a wheel mounted for rotation

between the arms of said forks, arms secured to said forks near their tops, a connecting bar secured at its ends to the ends of said arms, a steering post pivotally mounted in 50 an opening in said transverse bar, a crank arm secured to the lower end of the steering post, said crank arm being located in parallel relation with the other arms and pivotally connected to the connecting bar whereby 55 when the steering post is rotated the wheels will be rotated through a corresponding angle, a drive wheel located near the rear ends of said frame members, an axle for the drive wheel, said axle having two opposed crank arms, a seat, a pair of pivoted 60 pedals secured to the frame in front of said seat and connecting rods from said pedals to the cranks on the rear axle.

2. A toy vehicle comprising, in combination, 65 a base frame having two side members, a cantilever spring secured to the underside of each side member near the front end thereof, a transverse bar connected to the free ends of said springs, a U-shaped yoke 70 member pivotally attached to each end of said transverse bar, an arm secured to each yoke member, a steering post rotatably connected with the transverse bar at a point intermediate its ends, said steering post 75 having its lower end bent at right angles and flattened, a connecting bar connecting the free ends of said arms, the free end of the flattened portion being connected with the connecting bar so that when the steering 80 post is rotated the wheels will be rotated through corresponding angles, a seat secured to said members, a drive wheel pivotally connected at a point to the rear of the seat, a pair of oscillatable pedals connected to the 85 side members at a point located at the front of the seat, two opposed cranks connected with the drive wheel and a connecting rod joining each pedal with one of the said cranks.

In testimony whereof I affix my signature.
IRA G. NICKS.
